UNITED STATES PATENT OFFICE

CHARLES W. DAKE, OF CHICAGO, ILLINOIS, ASSIGNOR TO THE PYLE-NATIONAL COMPANY, OF CHICAGO, ILLINOIS, A CORPORATION OF NEW JERSEY

LATCH FOR HEADLIGHTS AND THE LIKE

Application filed November 7, 1927. Serial No. 231,586.

My invention relates to improvements in latches for headlights and the like and has for one object to provide a new and improved form of latch or closure which will lock the headlight door so as to make a tight snug closure and which will be easily and conveniently adjusted so as to take care of variations of the size and shape of the parts and so as to compensate for wear. Another object is to provide a latch which has a kick out or opening effect. Other objects will appear from time to time throughout the specification and claims.

My invention is illustrated more or less diagrammatically in the accompanying drawings, wherein—

Figure 1 is a detail side elevation showing the latch in the closed position;

Figure 2 is a front view;

Figure 3 is a plan view;

Figure 4 is a side elevation showing the latch in the open position with the door about to raise the latch to permit engagement;

Figure 5 is a side elevation showing the latch about to open the door;

Figure 6 is a perspective view of the adjusting sleeve;

Figure 7 is a detail perspective of a modified form of latch.

A is a housing, A¹ a door suitably pivoted on the housing in any suitable manner not here shown. It will be noted that the housing and the door make a snug fit one with the other. A² is a bracket mounted on the housing. It has an arm A³ extending forwardly from the housing adapted to overlie and engage the outside of the door. A⁴ is a pivot pin mounted on the bracket A². A⁵ is a lug on the door adapted to overlie and engage the lug A³ to assist in positioning the door with respect to the housing.

B is the latch. It has a hub B¹ rotatable on the pin A⁴ held in place thereon by a washer B² and castellated nut B³ with cotter pin B⁴. Extending forwardly from the sleeve B¹ is the hook element B⁵ having a generally cylindrical pin engaging surface B⁶, an outwardly inclined cramping surface B⁷ and an upwardly inclined handle B⁸. B⁹ is a kick out foot projecting downwardly from the sleeve

B¹ and adapted when the parts are in the position shown in Figure 5 to engage the front face of the lug A⁵ to open the door.

C is a latch pin on the cover; C¹ is an eccentric adjustable latch sleeve rotatable on the pin C. This latch sleeve has a plurality of spaced apertures C² therein. C³ is a locking screw which may pass through diametrically opposed apertures C² and through an aperture in the pin C¹ to hold the eccentric sleeve rigidly in adjusted position on the pin C, the screw being on the lower side or the side where the head will not come in contact with the latch. It will be noted from the arrangement shown in Figure 4 that as the door closes with the latch in its closed position the latch handle will be engaged by the pin so that the door will tend to open the latch camming the latch up as shown in Figure 4 until the surface B⁷ comes into engagement with the eccentric adjusting sleeve when the operator may rotate the handle downwardly and cam the door shut.

It will be understood of course that while I have shown my latch as applied to a headlight or lantern door, the latch may be equally as well applied to any door where it is possible for the door to close in a direction parallel with the latch and where it is possible to have the latch and holding pin project laterally beyond the edge of the door and it will also be understood that this latch might be used for any type of closure such as boxes and the like and while I have shown the eccentric adjustment as associated with the holding pin and not with the latch it will be obvious that any arrangement of parts whereby the effective distance between the pivoted screw and that part of the pin where it engages may be adjusted, will accomplish the purpose as is accomplished in the preferred form shown. Such an arrangement might take the form of an eccentric bearing for the hook quite as well as the eccentric bearing for the sleeve.

F is a stop associated with the latch pivot and F¹ is a limit member on the latch adapted to engage the stop to limit the motion of the latch downward through the locking position whereby the latch can never fall appre-

ciably below the position shown in Figure 1 so as to insure that movement of the door toward the latch will always find the latch in such position that it can be cammed open for 5 engagement by contact with the holding pin.

I claim:

1. In combination with a latch for doors and the like, a holding member adapted to be engaged by the latch and means for adjusting 10 the distance between the latch engaging portion of the holding member and the latch support, said means comprising a pin, an eccentric sleeve rotatable thereon, means for locking the sleeve in adjusted position.
- 15 2. The combination with two movable elements of means for locking them together comprising a latch pivoted on one and a holding member carried by the other, means carried by the latch for engaging the holding 20 member and locking the two elements together, a plurality of cams carried by the latch, one of them adapted when the latch is rotated away from the locking position to force the two elements apart, another 25 adapted when the latch is rotated toward the locking position to draw the two elements together, a third adapted when the two elements move toward one another to raise the latch to permit it to engage the holding member. 30
3. The combination with two movable elements of means for locking them together comprising a latch pivoted on one and a holding member carried by the other, stops associated with the latch to limit its motion toward and from the locking position, a cam carried by the latch adapted to be engaged by the holding member to rotate the latch into the open position upon movement of one of 35 the elements toward the other, this cam being located on and made a part of the latch handle. 40

Signed at Chicago, county of Cook and State of Illinois, this 20th day of October 45 1927.

CHARLES W. DAKE.
